DOOR AND WINDOW STRUCTURE FOR
CONVERTIBLE BODIES

John W. J. Ackermans, Detroit, Mich.

Application December 22, 1947, Serial No. 793,272

5 Claims. (Cl. 296—45)

1

This invention relates to vehicle bodies, and more particularly to vehicle bodies of the four-door convertible sedan type such as are commonly used on automobiles.

In some present constructions of this type, a center pillar separates the front and rear doors on each side, and above this pillar, separating the front and rear window frames carried by the respective doors, is an upper pillar which, when the top is lowered, may be either left erect, folded inwardly or wholly removed and stored until the top is to be put up again.

In other convertible tops of this type, the upper pillar is adjustably and replaceably fixed to the lower center pillar only. In place of the lower center pillar a center panel is sometimes used. Said upper pillar may be substituted by a center window the frame of which is secured to the lower pillar or center panel at the belt line of the vehicle. This construction, however, is not entirely satisfactory from the standpoint of esthetic considerations, and also because of the difficulty of aligning the center window frame with the frames of the front and rear doors' slideable, foldable or stationary upper window frames; also because the center window frame projects forwardly so far as to restrict shoulder room and thus interferes with easy entrance to the vehicle.

To eliminate these objectionable features, the present invention provides a heavy center window pane, without outer frame, which is carried by the upper part of one of the doors, thereby eliminating the center window frame and its inner weatherstrip, if desired; also only one door gap joint has to be aligned with the center window and the means of securing the center member to the top of the lower center pillar are no longer necessary. This combination center window and upper door channel extension makes also a more rigid construction.

An object of the present invention is to provide a convertible four-door sedan type body of improved design and operability.

A further object of the invention is to provide a body of the type indicated having improved appearance features, and wherein assembly of the parts in manufacture is facilitated.

Further objects and advantages of the invention will be apparent from the following description, taken in connection with the appended drawings, in which:

Fig. 1 is a side elevation of a four-door convertible sedan type automobile embodying a form of the invention including a center window.

2

Fig. 2 is an enlarged view, partly broken away, of the center window and its associated elements, and corresponds to a view looking in the direction of the arrow 2 in Figure 3.

Fig. 3 is a sectional view of the same, taken on the line 3—3 of Fig. 1.

Fig. 4 is a plan view of the same, taken on the line 4—4 of Fig. 2.

Fig. 5 is a fragmentary view taken on the line 10 5—5 of Fig. 2.

Fig. 6 is a sectional view taken on the line 6—6 of Fig. 2.

It is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Figures 1 to 6 illustrate a four-door sedan having a convertible top designed to fold into a booth at the rear of the car body, but shown in Figure 1 in its extended or raised position and secured at its forward edge in a substantially vertical plane to a rearward extension 12 of the windshield frame 14. The body of the vehicle comprises front and rear doors 16 and 18 which open toward the front, the rear door being hung on a pillar 20 by means of concealed hinges 22. The axis of the hinges is indicated in Figures 1, 3 and 4 by the reference numeral 23.

The doors 16 and 18 are provided with fixed channel frames 28 and 30, each of which contains a rubber or felt runway 29 (Figure 5) which is channeled to receive the edge of the window glass in vertically sliding relation. The frames 28 and 30 are fixed to their respective doors 16 and 18, the panes 24 and 26 being vertically slideable therein to concealed positions in the doors, in the usual manner. The body is also provided with ventilating windows 32 and windshield panes 34, which may be of usual construction. There may also be provided a pair of overhead panes 36 in the extension 12. The belt molding of the vehicle is indicated at 38.

Between the front and rear side windows is mounted a center window pane 40 which is formed of heavy glass of approximately the thickness of the frames 28 and 30. In the embodiment shown in Figures 1—6, the pane 40 is formed with a groove in each of its edges, and a pair of inserts 42, 43, of metal or other material, 50 55 are inlaid and cemented along said groove and

are secured together as by dowel pins 44. The chief function of the inserts 42, 43 is to furnish securing means for certain elements described hereinafter, and also to improve the appearance of the window by eliminating the conventional channeled metal frame. In place of the inserts 42, 43, plug-filled holes in the edges of the pane may be used.

An arm 46 is secured, as by welding, to the inner surface of the upper channel of window frame 30, as indicated in Figures 2 and 5, and extends forwardly thereof, being secured to the insert 42 by means of machine screws 48. A second arm 50 is secured to the lower forward surface of the frame 30 and extends forwardly thereof, being secured to the insert 43 by means of machine screws 52. A flexible rubber weatherstrip 54 of channel shape is interposed between the arm 50 and the insert 43 and is designed to cooperate with a series of molding strips 56 secured to the upper surfaces of pillar 20 and of the front and rear doors, to act as a dam to minimize leakage between the pane 40 and said upper surfaces while permitting lateral or angular movement therebetween.

At the forward edge of pane 40 is secured an inner weatherstrip 58 having a forwardly projecting flange designed to fit against the front window frame 28 to form a weatherproof seal. The rear edge of pane 40 is provided with a joint seal as described below.

As seen in Figure 3, the top 10 comprises a rigid side rail extending longitudinally of the vehicle and comprising members 62 and 64 which are permanently secured together and act to support the fabric wall 66 of the top which, as indicated at 67, extends downwardly along the outer surface of the rail to form a weatherproof seal, in known manner.

A retainer 68 is secured to the members 62 and 64 and serves in turn to secure a channel-shaped flexible weatherstrip 70, of known construction. To the weatherstrip 70 is secured a second channel-shaped weatherstrip 71 having a flexible inner flange 72 and a flexible outer flange 74 which cooperate with the pane 40 and arm 46 to form a weatherproof seal while permitting movement therebetween. The arm 46 is depressed, if necessary, as indicated at 76 to permit it and the pane 40 to clear the lower edge of member 64.

In the embodiment thus far described, it will be seen that the pane 40 is fixed to and carried by the rear door 18, so that as the door 18 is opened, it and the pane 40 will rotate about the hinge axis 23 from the positions shown in full lines in Figures 3 and 4 to the positions shown in broken lines in the same figures. In so doing, the forward portion of the pane will bend the inner flange 72 of the weatherstrip 71 out of its path, and similarly the rear portion of the pane will bend the outer flange 74 out of its path. The weatherstrip 54 at the lower edge of the pane will also be deformed to permit it to pass the molding strip 56. The flanges of both these weatherstrips are sufficiently resilient to return to normal position after deformation.

As will be seen in Figures 4 and 6, the pane 40 does not lie in the plane of pane 24, nor in the plane of pane 26, but in a plane disposed at a small angle thereto, so as to follow the side contour of the body. The joint space between the pane 40 and the frame 30 is sealed by means of a wedge-shaped rubber seal 78 which is compressed between the rear edge of pane 40 and

the front edge of channel 30 by screws 79 as shown in Figure 6.

Although the invention has been described with reference to a particular embodiment thereof, it may be embodied in other forms within the skill of artisans in this art, and is not limited except by the terms of the following claims.

I claim:

1. A vehicle body having at each side a lower center pillar and two doors provided with windows spaced from each other longitudinally of the body, a permanently erected transparent panel disposed between said windows and having edges formed with a groove, an insert in said groove, supporting means on one of said doors for carrying said panel, removable fastening mechanism coacting with said supporting means and with said insert for retaining said panel, and weatherstripping secured to at least one side of said insert by said fastening mechanism, said supporting means comprising a guide channel for sliding one of said windows from a closed position to an open position.

2. A vehicle body having at one side a lower center pillar and two doors provided with slideable windows, a permanently erected transparent panel longitudinally disposed between said windows and having edges formed with a groove, an insert in said groove, supporting means on one of said doors fixedly securing said panel to one of said doors, said insert comprising fastening mechanism along at least one of said edges for retaining removable weatherstripping, and removable fastening mechanism coacting with said insert to retain said weatherstripping in place, said panel being capable of withstanding breaking under normal use of said vehicle body, said supporting means including a runway channel to receive an edge of the slideable window associated with said one door.

3. In a vehicle body comprising a roof, front and rear doors, and a pillar separating said doors, a vertically slideable window carried by one of said doors and movable to a point above the top of said pillar, supporting means comprising a runway channel for at least one edge of said window secured to one of said doors, arms connected to said supporting means, a transparent panel carried by said arms and constituting an extension of said pillar, the edges of said panel being formed with grooves, inserts in said grooves substantially flush with said edges, and removable fasteners engaging said supporting means, arms and said inserts to secure them together.

4. A vehicle body having at one side a lower center pillar and two doors provided with spaced windows, a permanently erected transparent panel disposed between said windows and having edges formed with recesses, inserts provided with fastening mechanism positioned in said recesses, supporting means on one of said doors for carrying said panel, removable fastening mechanism coacting with said supporting means and with said inserts for retaining said panel, and weatherstripping along at least one of said edges secured to said inserts by said removable fastening mechanism, said supporting means comprising a guide channel for sliding one of said windows from a closed to an open position.

5. In a vehicle body having a main body portion terminating in a longitudinal belt line, a collapsible top for said body, front and rear closures at one side of said body including doors terminating at said belt line, a pillar separating said doors and terminating at said belt line, said

closures including longitudinally spaced slidable windows carried by said doors and movable to a level above said belt line, supporting means fixed to one of said doors including a runway channel for one of said windows, a panel of substantial width supported by said supporting means and forming a closure for the space between said windows above the pillar when the doors are closed, and means operative to form a weather seal between said panel and the other 10 closure when said doors are closed.
